DESIGN FOR A HANDBAG

Samuel R. Goldsmith, New York, N. Y.

Application December 28, 1937, Serial No. 73,911

Term of patent 3½ years

To all whom it may concern:

Be it known that I, Samuel R. Goldsmith, a citizen of the United States, and resident of New York city, Borough of Manhattan, in the county and State of New York, have invented a new, original, and ornamental Design for Handbags, of which the following is a specification, reference being had to the accompanying drawing, forming a part thereof, and of which Figure 1 is a view in front elevation and Fig. 2 is a view in end elevation of a handbag showing my new design.

I claim:

The ornamental design for a handbag, substantially as shown.

SAMUEL R. GOLDSMITH.
